CIRCUIT INTERRUPTER

John B. MacNeill and Fritz E. Florschutz, Pittsburgh, Pa., assignors to Westinghouse Electric Corporation, East Pittsburgh, Pa., a corporation of Pennsylvania

Application February 26, 1953, Serial No. 339,082

11 Claims. (Cl. 200—150)

This invention relates to circuit-interrupters in general, and more particularly to circuit-interrupter tank constructions for relatively high-voltage circuit interrupters.

In U. S. patent application Serial No. 174,107, filed July 15, 1950, now U. S. Patent 2,693,519, issued November 2, 1954 to Benjamin P. Baker and Winthrop M. Leeds, and in U. S. patent application Serial No. 174,012, filed July 15, 1950, now U. S. Patent 2,743,337, issued April 24, 1956, to Fritz E. Florschutz and Wayne S. Aspey, both said applications being assigned to the assignee of the instant application, there are disclosed and claimed circuit-interrupter tank constructions of novel configuration utilizing a minimum quantity of liquid, such as oil. In liquid-break circuit interrupters, the liquid, such as oil, must be removed periodically from the circuit-interrupter tanks, the extinguishing units inspected after the tanks have been emptied, and necessary filtering and reclaiming operations performed upon the removed oil prior to its replacement within the circuit-interrupter tanks. Any steps taken in the direction of diminishing the liquid content of the circuit-interrupter tanks without decreasing necessary electrical clearances are steps taken in the right direction, and the aforesaid applications are concerned with tank constructions utilizing a minimum liquid content without, however, creating a hazardous condition by decreasing electrical clearances below the requisite level.

It is an object of the present invention to further improve upon the tank constructions disclosed in the aforesaid two applications by providing a construction which is cheaper to manufacture, more pleasing in appearance, and at the same time being rugged and having the requisite mechanical strength under the high-pressure conditions encountered during the interruption of high-power circuits.

Another object is to provide an improved tank construction in which the accurate plumbing is easily obtained prior to mounting the leg fixtures to the tank.

Another object is to provide an improved tank construction involving a minimum of liquid content.

A further object is to provide an improved method of manufacturing a circuit-interrupter tank so that the burnoff edges will be in a single vertical and accurate plane.

Further objects and advantages will readily become apparent upon reading the following specification, taken in conjunction with the drawings, in which:

Figure 1 is a side elevational view of a circuit interrupter embodying our improved tank construction with the terminal bushings partly broken away;

Fig. 2 is an end elevational view of the tank shown in Fig. 1;

Fig. 3 is an enlarged vertical sectional view taken through the tank of Figs. 1 and 2, showing the interior construction including a pair of arc-extinguishing units, the contact structure being shown in the closed-circuit position;

Fig. 4 is a fragmentary sectional view taken along

2

the line IV—IV of Fig. 3 illustrating the lift rod linkage in the closed-circuit position thereof;

Fig. 5 is a side elevational view of one of the shapes, or tank halves, utilized in the present invention;

Fig. 6 is a top plan view of the shape of Fig. 5;

Fig. 7 is a vertical sectional view through the shape of Fig. 5, taken along the line VII—VII thereof;

Fig. 8 is an enlarged sectional view through one of the flat spots shown in the shape of Fig. 5 taken along the line VIII—VIII thereof; and

Fig. 9 is a somewhat diagrammatic view of the method of performing the burnoff operation of a tank half.

Referring to the drawings, and more particularly to Figs. 1 and 2 thereof, there is shown a circuit interrupter 1, generally of the high-voltage type including a pair of terminal bushings 2, 3, preferably of the condenser type, which extend downwardly within the tank 4 in a manner more clearly shown in Fig. 3 of the drawings.

Disposed at the lower interior ends of the terminal bushings 2, 3 are a pair of serially related arc-extinguishing units, generally designated by the reference character 6. These units 6 may be of the type set out in the U. S. patent application, Serial No. 311,766, filed September 26, 1952, now U. S. Patent 2,760,032, issued August 21, 1956, to Benjamin P. Baker and George B. Cushing, and assigned to the assignee of the instant application. Generally the units 6 are of the type which establish a pressure-generating arc and a serially related interrupting arc, with the pressure-generating arc forcing liquid, such as oil, under pressure toward the interrupting arc to effect the latter's extinction. The contact structure is such as to establish the two breaks of each unit 6 substantially simultaneously. The particular construction of the units 6 is not important to an understanding of the present invention; consequently, a description of their details is not given, and reference may be had to the aforesaid application, Serial No. 311,766 for any further description of their operation that might be desired.

As indicated in Fig. 3, the units 6 are electrically interconnected and actuated by a conducting cross-bar, or bridging member 7, which is actuated vertically in a reciprocal manner by an insulating lift rod 8. The lift rod 8 is operated by a lift-rod linkage, generally designated by the reference character 10, and more clearly shown in Fig. 4 of the drawings. With reference to Figs. 3 and 4 it will be observed that a rod 11 (Fig. 1) mechanically interconnects the several poles of the circuit interrupter, only one pole being shown in Figs. 1-3.

As well understood by those skilled in the art, for interrupting a three-phase electrical circuit, three such poles, or circuit interrupters 1, are arranged upon the same platform and are electrically and mechanically interconnected so that they will open and close simultaneously.

The operating rod 11 shown in Fig. 1 extends across the tops of all of the circuit interrupters 1 (only one being illustrated) and serves to actuate them simultaneously. As indicated in Fig. 3, the operating rod 11 has bifurcated portions 11a, through which pass pivot pins 12 which serve to interconnect the rod 11 with one or more crank arms 13. Each crank arm 13 has its lower end fixedly secured, or clamped, to a shaft 14, the latter extending through the two side plates 15, 16 of a tank top assembly 17. Generally the tank top assembly 17 includes a pair of flange plate assemblies 19 and a lever box 20. Each flange plate assembly 19 forms a support for its respective terminal bushing 2, 3, and the two flange plate assemblies 19 and the lever box 20 are welded together initially and positioned as a unit within the top of the tank 4, as more clearly described hereinafter.

As shown in Fig. 4, clockwise rotation of the shaft 14, as caused by the connecting rod 11, will cause corresponding clockwise rotation of the toggle lever 22, the latter being biased in said direction by a toggle accelerating spring 23. Clockwise rotation of the toggle lever 22 will cause motion of the toggle link 24 to cause clockwise rotation of toggle lever 25, the lower end of which is mounted on a stationary pin 26. The pin 26 is mounted between the two side plates 15, 16 of the lever box 20. Cooperating with the toggle lever 25 is a triangularly-shaped toggle link 27, one end of which is pivotally connected to a guide link 28, the upper end of which is pivotally mounted on a stationary pivot 29. The toggle link 27 is also pivotally connected to the upper end of the insulating lift rod 8 as shown in Fig. 4 to effect actuation of the same. Counterclockwise rotation of the shaft 14, when the interrupter is in the open circuit position (not shown) will cause straightening of the toggle 18 comprising the toggle lever 25 and the toggle link 27, which action, in turn, will be accompanied by resetting of the toggle 30 including the toggle link 24 and the toggle lever 22 against the biasing action exerted by the toggle accelerating spring 23.

Thus, opening and closing operations of the bridging member 7 are effected by actuation of the lift rod linkage 10, in turn caused by horizontal reciprocal movement of the operating rod 11 across the several interrupters 1, and effected by any suitable pneumatic or electrical mechanism forming no part of our invention.

One feature of our invention is particularly concerned with the construction of the tank 4 in an economical manner, and with the result of such fabrication being a strong and rigid tank capable of withstanding high internal pressure. We construct the tank 4 from two tank half shapes, generally designated by the reference character 31 in Figs. 5-7. Each shape 31 is formed from a blank of sheet metal. In a particular commercial application, the shape 31 is formed from one-half inch steel plate. The shape results from pressing the original blank into a die, and forming or pressing the blank into the configuration shown in Figs. 5-7 of the drawings.

The resulting shape or dished member 31 forms one half of the circuit breaker tank 4. The remaining half is formed in a similar operation in a single die, and the two shapes 31 are welded together along their peripheral edges with the upper end of the tank 4 left open for the insertion therein of the tank top assembly 17. It will be observed that three flat spots 32 are formed in the side of the dished member 31 by the die. These three flat spots 32, the configuration of which is more clearly shown in Fig. 8, form a support for a three-legged tool support 33, more clearly shown in Fig. 9 of the drawings. The tool support 33 includes a plate 34 having three legs 35, the lower ends of which rest upon the three flat spots 32. Disposed upon the plate 34 is a guide ring 36 against which bears an acetylene burnoff torch 37. The torch 37 may be moved about the guide ring 36 by a motor, or it may be moved manually. The guide ring 36 insures that the tip 38 of the torch 37 will be a predetermined fixed distance from the periphery 39 of the shape 31 after it comes from the die. If desired, a water nozzle may follow in the wake of the burning action of the torch 37 to minimize warpage due to the burnoff heat.

By having the three flat spots 32 provided on the die, and formed in the side of the shape 31, there is assurance that the burnoff operation will take place in a single plane, which eventually will be the vertical seam of the finished tank 4. Moreover, the three flat spots 32 provide a desirable means of supporting the shape 31 by pillars 40 from a base 41 during the burnoff operation.

Not only does the die form the flat spots 32, but also it forms two plumb-line marks 43 (Fig. 5) along the center line 44 of the shape 31. Thus, after the burnoff operation and following welding of the two sides, or

halves, 31 together, it is possible to set the tank up so that the seams 45 (Fig. 2) are vertical and the plumb-line marks 43 (Fig. 5) are also arranged to be vertical, so that the leg supports 46 of the tank 4 may then be placed in the proper position and welded to the lower portion of the tank 4.

It will be apparent from the foregoing operations that the tank 4 is mounted vertically with respect to two of its axes prior to securing the legs 46 in place. One axis is determined by the vertical seams 45 (Fig. 2) resulting from welding the two shapes 31 together. The other axis is determined by an alignment of the two plumb line marks 43 (Fig. 5) formed on the shape 31 while the latter is in the die. Thus, the tank 4 is positioned in a true and accurate vertical alignment before the legs 46 are welded into place.

Referring to Fig. 7, it will be noted that at the upper open end of each shape 31 there is provided a short vertical side-wall portion 48, which in one particular instance was three and one-fourth inches long. In other words, the entire open periphery 49 of the shape 31 is formed with the walls thereof vertical. This has the advantage that following the welding of the two shapes 31 together, the tank top assembly 17 (Fig. 3) may be placed interiorly within the open upper end of the tank 4, and lowered to a point where the center-line of the shaft 14 is a fixed distance "D" from the base plates 50 welded to the lower ends of the legs 46. This has the advantage that the operating rod 11 may be maintained horizontally in its passage through the housings 51 (Fig. 3) of the several tank top assemblies 17. When the tank top assembly 17 has been moved vertically within the side-wall portion 48 so that the center-line of the shaft 14 is at the predetermined distance "D" from the base plates 50, the sides of the tank top assembly may then be welded to the inner wall of the tank 4. The foregoing construction means that a certain vertical adjustment of the tank top assembly 17 is possible without unnecessarily increasing the weld gap between the tank top assembly 17 and the inner walls of the tank 4.

From the foregoing description it is apparent that we have provided a rugged and strong circuit interrupter tank formed from a pair of mating tank halves welded together, each half being initially burned from a steel or metal plate, and subsequently preformed to the desired shape in a die. As a practical matter in using only a single die it may be necessary to press the blank only partially into the die, remove the blank and reheat it. It may then be replaced in the die and further pressing take place. Actually the blank may be formed by three pressing operations before it assumes the desired configuration. The die not only provides the flat spots 32 but also forms the plumb-line scoring marks 43.

The foregoing description shows how we have utilized the flat spots 32 in conjunction with a suitable three-legged tool support 33 to provide a burnoff operation along a single accurate and predetermined plane.

It will be noted that with our improved tank configuration the width "W" of the top of the tank 4, as viewed in Fig. 3, is greater than the width "L" of the tank 4 in Fig. 3 adjacent the mid-portion of the tank 4. This is indicated by the lateral distance "S" in Fig. 1, and serves to provide adequate mounting space for the current transformers 52, which control the relaying operations. By having the width "L" of the mid-portion of the tank 4 less than that of the top of the tank 4, as viewed in Fig. 3, the liquid content is further decreased over that set out in the first two mentioned applications, and therefore facilitates reclaiming operations of the oil.

From an overall standpoint, however, it may be stated that generally the entire length of the side seams 45 (Fig. 2) are generally parallel to each other when the tank 4 is viewed in side elevation as shown in Fig. 1.

Viewing Fig. 2, it will be noticed that the thickness "t" at the top of the tank 4 is less than the thickness "T"

adjacent the mid-portion of the tank. This fact further minimizes the liquid content of the tank 4.

Viewing Fig. 6, it will be apparent that horizontal sections taken through the tank 4 are of oval shape.

From the foregoing description it is apparent that the tank 4 is more economically manufactured, the fabrication time is reduced, the result is stronger and more rugged than tank constructions heretofore known in the art and the accurate alignment of the legs 46 and the vertical positioning of the tank top assembly has been expedited.

Although we have shown and described a specific structure and method of forming the same, it is to be clearly understood that the same were merely for the purpose of illustration, and that changes and modifications may readily be made therein by those skilled in the art without departing from the spirit and scope of the invention.

We claim as our invention:

1. The combination in a circuit interrupter tank of a pair of cooperating metallic dished members open at one end and having meeting edges at their sides and along a curved line at the other end, the sides of each dished member being generally parallel to each other, and means securing the meeting edges of two dished members together along their sides and along the curved line at said other end.

2. The combination in a circuit interrupter tank of a pair of cooperating metallic dished members open at one end, each dished member having generally parallel sides, the two dished members being joined directly to each other along substantially the whole of their periphery, and a tank top assembly enclosing the open ends of the dished members.

3. A circuit interrupter including a tank, a pair of terminal bushings extending into the tank adjacent the top of the tank, a pair of arc-extinguishing units carried by the interior ends of the terminal bushings, horizontal sections taken through the tank being of oval shape, and the width of the top of the tank taken in the plane passing through the two terminal bushings being greater than the width of the tank in said plane adjacent the mid-portion of the tank.

4. A circuit interrupter including a tank, the tank including a pair of open-ended dished members, means securing the two dished members together along a substantial portion of their periphery, the open ends of the dished members having vertical side portions at least for a short distance, a tank-top assembly fitting within the open end of the tank at the vertical side portions, the arrangement permitting the tank-top assembly to be positioned a predetermined distance from the bottom of the tank without increasing the weld gap between the tank-top assembly and the inner walls of the tank.

5. A circuit interrupter including a tank, a pair of terminal bushings extending into the tank adjacent the top of the tank, a pair of arc-extinguishing units carried by the interior ends of the terminal bushings, horizontal sections taken through the tank being of oval shape, and the width of the top of the tank taken in the plane passing through the two terminal bushings being as wide as at the portion of the tank at which the extinguishing units are disposed.

6. A circuit interrupter tank having an upper open end portion, the open end portion having a short length of vertical side walls, a tank top assembly fitting within the open end portion, and the construction permitting the tank top assembly to be positioned vertically at the place desired with a constant weld gap.

7. A circuit interrupter including a tank, arc-extinguishing means disposed within the tank, the two sides of the tank including two formed dished pieces secured together, each dished piece having a rounded bottom and generally parallel side portions with the edges of the side

portions and the bottom being in a single plane, and each piece being more dished adjacent its bottom than near its top so that the thickness of the top of the tank is less than the thickness of the tank adjacent the mid-portion thereof.

8. A circuit interrupter including an upstanding tank, a pair of terminal bushings diverging away from each other in an upward direction and extending within the tank at the upper end thereof, arc-extinguishing means disposed interiorly within the tank and associated with the interior ends of the terminal bushings, said tank including a pair of cooperating whole side tank halves secured directly to each other in a plane extending substantially through the axes of the terminal bushings, each tank half being dished with a rounded bottom and with sides generally parallel to each other and with an open top so that when viewed in side elevation perpendicularly to said plane the entire sides of the tank are generally vertical and generally parallel to each other, and horizontal sections taken through the tank being of oval shape.

9. A circuit interrupter tank having a pair of terminal bushings extending into the upper end thereof, said terminal bushings diverging away from each other in an upward direction, the lower ends of the terminal bushings extending interiorly within the tank adjacent the mid-portion thereof, arc-extinguishing means associated with the interior ends of the terminal bushings, the bottom of the tank being rounded when viewed in side elevation perpendicularly to the plane extending through the axes of the terminal bushings and the sides thereof having a width adjacent the top thereof as great as the width adjacent the mid-portion thereof, and horizontal sections taken through the tank being of oval shape with the major axes of the ovals being substantially in said plane.

10. A liquid break circuit interrupter including an upstanding tank at least partially filled with an arc extinguishing liquid, an oval head for the tank having a pair of flat surfaces disposed at an angle relative to each other, a pair of terminal bushings extending into the upper end of said tank each terminal bushing supported perpendicularly to one of said flat surfaces, said terminal bushings diverging away from each other in an upward direction, the lower ends of the terminal bushings converging toward each other within the tank and extending adjacent the mid-portion thereof, an arc extinguishing unit associated with the interior end of each terminal bushing, a conducting cross-bar electrically interconnecting the arc extinguishing units and adapted to effect the actuation thereof, the bottom of the tank being rounded when viewed in side elevation perpendicularly to the plane extending through the axes of the terminal bushings and the sides thereof having a width adjacent the top thereof as great as the width adjacent the mid-portion thereof, said conducting cross-bar being movable substantially in said plane, and horizontal sections taken through the tank being of oval shape with the major axes of the ovals being substantially in said plane within which the conducting cross-bar moves.

11. A circuit interrupter tank having a pair of terminal bushings extending into the upper end thereof, said terminal bushings diverging away from each other in an upward direction, the lower ends of the terminal bushings extending interiorly within the tank adjacent the mid-portion thereof, arc-extinguishing means associated with the interior ends of the terminal bushings, said tank including a pair of cooperating whole side tank halves secured directly to each other in a plane extending substantially through the axes of the terminal bushings, the bottom of the tank being rounded when viewed in side elevation perpendicularly to said plane and the sides thereof having a width adjacent the top thereof as great as the width adjacent the mid-portion thereof, and

horizontal sections taken through the tank being of oval shape with the major axes of the ovals being substantially in said plane.
